(57) **CLAIM**

The ornamental design for a prayer pillow, as shown and described.

DESCRIPTION

FIG. 1 is a front perspective view of a prayer pillow, showing our new design;

FIG. 2 is a front elevation view thereof;

FIG. 3 is a rear elevation view thereof;

FIG. 4 is a left-side elevation view, the right-side elevation being a mirror image thereof;

FIG. 5 is a top plan view thereof;

FIG. 6 is a bottom plan view thereof; and,

FIG. 7 is an exploded top plan view of the prayer pillow shown in a detached condition.

The broken lines shown in the drawings depict portions of the prayer pillow that form no part of the claimed design.

1 Claim, 4 Drawing Sheets
